Des. 197,854
Patented Mar. 31, 1964

197,854

CUTLERY HOLDER

James L. Hvale, Chicago, and Austin Herbert Munson,
Arlington Heights, Ill., assignors to Ekco Products Com-
pany, Chicago, Ill., a corporation of Delaware

Filed Dec. 17, 1963, Ser. No. 77,834

Term of patent 14 years

(Cl. D44—29)

FIG. 1

FIG. 2

FIG. 3

FIG. 4

FIG. 5

FIG. 1 is a front elevational view of a cutlery holder showing our new design.

FIG. 2 is a side elevational view thereof as the same appears when viewed from the right hand side of FIG. 1.

FIG. 3 is a side elevational view showing the holder as viewed from the left hand side of FIG. 1.

FIG. 4 is an end view of the article as the same appears from the bottom end of FIG. 1.

FIG. 5 is an end view as the holder will appear when viewed from the top of FIG. 1.

We claim:
The ornamental design for a cutlery holder, as shown.
